WASTE MACHINE

Chadwick P. Smith and James R. Pangle,
Charlotte, N. C.

Application June 6, 1947, Serial No. 752,940

6 Claims. (Cl. 19—88)

1

This invention is directed to a waste reducing machine, and in particular relates to a machine for restoring the waste accumulated during the operation of a cotton or textile mill back to fiber form so that the fiber can be reused.

Cotton waste machines, sometimes known as willow machines, all have a spiked drum or beater for shredding the waste, and either a blower fan or suction fan for removing dirt and debris from the shredded fiber and to assist in laying the shredded fiber onto a moving belt or table so that the fiber can be removed from the machine. Such machines are used to shred clean waste, even though no dirt is removed, as the air currents created by the fans are necessary to lay the fibers. These machines are bulky, complicated and expensive. Ordinarily, they require the use of a large bin or room into which the exhaust air is discharged to collect the dust and lint, the combination of dust or lint and air in the air ducts and bins or rooms constituting a severe fire hazard.

The objects of this invention are to produce a cotton waste machine of simple construction in which clean cotton waste can be shredded and laid without the use of suction or blower fans; to eliminate the use of air ducts, collecting bins or rooms with their accompanying fire hazard; to regulate the air currents in the machine so that the staple of the fibers is not broken; and to produce a machine having few moving parts and a high quality performance.

Generally these objects are obtained by constructing a machine having the usual beater for shredding the waste, and regulating the air blast from the beater by means of a cylindrical screen having a perforated cover thereover which communicates with atmospheric pressure to settle the fibers, the screen in turn assisting in the laying of the fibers.

The means by which the objects of the invention are obtained are more fully described with reference to the accompanying drawings in which:

Figure 1 is a top plan view of the machine;

Figure 2 is a side elevational view of Figure 1;

Figure 3 is an enlarged cross-sectional view along the line 3—3 of Figure 1; and

Figure 4 is an enlarged cross-sectional view on the line 4—4 of Figure 1.

As seen in Figures 1 and 2, the machine broadly is composed of an endless conveyor A upon which the cotton waste is deposited and fed to the beater and settling rolls contained in housing B, the fiber being ejected from the machine

2

on the conveyor table C. The machine may be constructed of single or multiple units, each unit consisting essentially of a beater and the screening means. Figures 1, 2 and 3 illustrate two units connected in tandem. Suitable gearing E is provided for driving the various conveyor belts, feed rolls, beaters and revolving screens.

Housing B is formed with side walls 2 and 4, a front wall 6 and rear wall 8. Mounted at the top of wall 6 are feed rolls 10 which seize the cotton waste from conveyor A and feed it into the housing B.

Mounted within housing B, so as to be substantially tangent to rolls 10, is the beater drum 12 of the first unit. This drum is provided with teeth 14 which tear the cotton into shreds as it is fed through rolls 10, and as the drum rotates counter-clockwise, carries the shreds toward the rear of the machine. A curved pan 16 extends beneath drum 12 from adjacent feed rolls 10 to a point rearwardly of the axis of the drum, at which point the pan terminates in a leather apron 17. Rearwardly and closely adjacent the lower half of the drum is a horizontal "knock-off" or baffle plate 18 which serves to remove any clumps of shreds which may be clinging to the teeth 14, and prevents air currents from blowing the fibers around the drum where they would become further shredded and their staple torn. A curved plate 19 extends from plate 18 to the top wall 9 of housing B, the lower edge of this plate being slightly spaced above plate 18. Drum 12 is surmounted by a cover 20, hinged at 22 to wall 9 so that the cover may be opened for inspection. In order that excess air be prevented from entering the housing, leather aprons 24 and 26 are secured to cover 20 and to pan 16, respectively, to lap rolls 10. Similarly leather apron 17 forms an air seal between pan 16 and endless belt 30. The air gap between plates 18 and 19 is closed by the leather apron 21.

Endless belt 30 is inclined upwardly and rearwardly for the purpose of laying the fibers in cooperation with cylindrical screen 32, and to deliver the shredded waste to the second of the tandem units. Screen cylinder 32 is journaled in the side walls of housing B and is spaced from $\frac{1}{2}$ to $1\frac{1}{2}$ inches from belt 30. Above cylinder 32 is a perforated cover 34 through which cylinder 32 communicates with the atmosphere. The perforations are approximately $\frac{1}{8}$ inch in diameter and extend over substantially the entire area of the curved cover. Cover 34 has a clearance ranging from $\frac{1}{2}$ to $1\frac{1}{2}$ inches above cylinder 32, and is hinged at 36 to top wall 9.

The use of the leather aprons to provide air seals between the various members of the machine is important in the maintaining of the air flow and pressures created by the rotation of beater 12. This principle is further followed by having a clearance between the side walls 2 and 4 and beater 12, belt 30, and cylinder 32 of $\frac{1}{8}$ inch or less. Pan 16, curved plate 19 located to the rear of beater 12, and "knock-off" plate 18, respectively, contact and are secured to each side 10 wall in substantially air tight fashion.

The operation of this unit is as follows:

Cotton waste is moved on conveyor A into feed rolls 10 which force the waste into contact with the teeth 14 on beater 12. The beater revolves at a speed depending on the type of waste being shredded, a typical speed being about 750 R. P. M. Teeth 14 tear shreds from the waste, the shredded material being thrown by impact and carried by the air blast created by the revolving beater, along the path of pan 16 and discharged into the compartment created by the beater, pan, belt 30, screen 32, and the contiguous side and top walls of housing B. Material sticking to teeth 14 is knocked off by plate 18 so that it is not carried around and around by the beater as such action would chew the fibers and tear down the staple. In the compartment the air pressure, resulting from the fan effect of beater 12, is above atmospheric pressure, with the air currents moving rearwardly and upwardly. The velocity of the air current is less, however, than that between pan 16 and beater 12, and consequently the heavier particles or shreds immediately settle on belt 30 and are moved thereon toward cylinder 32. Belt 30 and screen 32 are driven at much slower speeds than beater 12.

Lighter shreds are carried by the air current to cylinder 32 where the air passes through this screen, depositing the particles on the surface thereof. As the cylinder rotates, these fibers on the sieve are dropped on top of the heavier particles which were previously laid on belt 30, it being noted that air escapes through the top side of cylinder 32, through perforated cover 34, to the atmosphere.

Air currents also pass upwardly between the rear edge of plate 18 and cylinder 32, over the surface of cylinder 32 into the space between the cylinder and perforated cover 34, and outwardly through the perforations in the cover. The lightest particles, fiber shreds, or lint are carried by this air current upwardly over the surface of cylinder 32. As the air is passing through the surface of the cylinder, much of the shreds and lint are deposited on the cylinder and are brought down to the belt 30. Such shreds or lint as may be carried into the space between the top of cylinder 32 and cover 34 fall on top of the cylinder because the air drops to atmospheric pressure and substantially zero velocity as it escapes through the perforations in cover 34. The rotation of cylinder 32 brings this finally deposited matter down to belt 30.

It has been noted that cylinder 32 is spaced from $\frac{1}{2}$ to $1\frac{1}{2}$ inches above belt 30. The heavier particles of shredded cotton, at the beginning of a shredding operation, quickly pile up on belt 30 so that when moved beneath cylinder 32, are slightly compressed by the cylinder, and by filling the space between the cylinder and belt form, in effect, an air seal at this point. The bulk of the air is directed therefore through the screen surface of cylinder 32. The rotation of the cylinder continuously deposits the lighter fibers and lint

upon the heavier material. No material is carried through the full rotation of the cylinder 32 as the space rearwardly of the cylinder to the upper end of belt 30 is at substantially atmospheric pressure. It is also noted that there is sufficient flexibility in the belt 30 to allow for unequal thicknesses of material deposited upon belt 30 so that the space between the belt and cylinder will be filled without jamming.

Belt 30 passes the material to the feed rolls 10a of the second unit which is constructed and operates exactly as the first unit, the material passing from the beater 12a, guided by pan 16a, to belt 30a, and cylinder 32a, air being exhausted through perforated cover 34a, and the material being discharged on conveyor table C. A flexible metal plate 40 secured to the rear edge of top wall 9 has its free edge resting on belt 30a to form an air seal at this point.

The machine is characterized particularly in that the auxiliary suction or blower fans employed by prior art devices are eliminated, this being possible by using the air current created by beater 12 to deliver the shredded material to the space between the beater and cylinder 32, and by gradually dropping the air to atmospheric pressure by directing the bulk of the air through cylinder 32 and then through perforated cover 34. Although the machine has been described, for convenience, in the shredding of cotton waste, it is apparent that its utility extends to the shredding of all kinds of fibrous materials.

Having now described the means by which the objects of the invention are obtained, we claim:

1. In a waste machine having beater means for shredding waste fiber material, a compartment communicating rearwardly of said beater, an endless conveyor forming a movable bottom for said compartment, and a cylindrical rotatable screen forming the rear end wall of said compartment and slightly spaced from said conveyor, said compartment otherwise being substantially air-tight to channel air currents from said beater to said screen, the improvement comprising a perforated cover extending over said screen, whereby air currents flowing from said compartment through said screen are retarded by said cover when passing therethrough into the atmosphere.

2. In a waste machine as in claim 1, the further improvement comprising said cover being spaced from said screen to provide an opening between said screen and cover, and communicating with said compartment.

3. In a waste machine as in claim 2, the further improvement comprising a plate member secured to said machine adjacent said cover and having its free end yieldably resting upon said conveyor rearwardly of said screen, whereby said free edge will be lifted by and ride upon waste material being ejected from said machine to form an air seal between said member, said material and said conveyor.

4. In a waste machine as in claim 1, the further improvement comprising said cover being slightly spaced from and extending over a portion of the periphery of said screen to provide an opening between said screen and cover, and communicating with said compartment.

5. In a waste machine as in claim 4, said cover being of arcuate section and having perforations extending radially thereof.

6. In a waste machine having beater means for shredding waste fiber material, a compartment

communicating rearwardly of said beater, an endless conveyor forming a movable bottom for said compartment, and a cylindrical rotatable screen forming the rear end wall of said compartment and slightly spaced from said conveyor, said compartment otherwise being substantially air-tight to channel air currents from said beater to said screen, the improvement comprising a cover having openings therethrough extending over said screen and slightly spaced therefrom to provide communication with said compartment and the space between said cover and screen so that said air currents pass in part over and outwardly of said screen, the remaining air currents passing through said screen, whereby air currents flowing from said compartment over and through said screen are retarded by said cover when passing therethrough into the atmosphere.
